SYSTEM OF SYNCHRONIZING TELEVISION TRANSMISSIONS

Ulrich Knick, Berlin-Steglitz, Germany, assignor to Fernseh G. m. b. H., Berlin-Zehlendorf, Germany

Application April 13, 1940, Serial No. 329,568
In Germany December 30, 1937

3 Claims. (Cl. 250—36)

This invention relates to the synchronization of television transmissions, particularly to the synchronization of saw-tooth wave generators for deflection of electron beams, and is a refiling of application Serial No. 248,483 filed December 30, 1938.

Especially in so-called interlaced scanning the required accuracy of the deflecting waves is very great. If the transmitted synchronizing impulses are not accurately timed, which can happen under the influence of pick-up of interfering impulses, or if the frequency or phase of the synchronizing impulses varies because of power-line fluctuations, these defects, which may be small for the individual impulse, may become additive. If this happens to the line-synchronizing impulses, ragged picture edges may result. In the case of framing impulses, such variation may cause jumping of the entire picture in the vertical direction, which in turn results in pairing off of lines for interlaced scanning or complete loss of interlace.

It is the object of this invention to eliminate the above described defects. A further object of this invention is to hold the voltage or current amplitude reached at the end of each saw-tooth cycle constant.

Broadly considered, this invention provides the use of non-self-oscillatory circuits in which two conditions may prevail, according to the rising or declining portion of the saw-tooth wave to be produced; the first condition representing the charging period of a condenser, the second the discharging period of the same condenser. A switching impulse is used to introduce the second condition, while a derivative thereof is used to terminate the second condition and to re-introduce the first condition.

More specifically, an electron discharge tube may be used as a discharge path for the above-mentioned condenser, whereby this discharge tube is rendered conductive by an impulse and rendered non-conductive by a derivative thereof.

Still more specifically, the electron discharge tube can be rendered conductive by an impulse so as to discharge the aforementioned condenser, and, after the voltage across the condenser has reached a certain value, an impulse is released rendering the discharge tube non-conductive again.

Other objects, features and advantages of this invention will become apparent from the following description taken in connection with the accompanying drawing, showing embodiments of the invention, in which:

Fig. 1 shows a circuit for producing saw-tooth voltage waves;

Fig. 2 shows a circuit for producing saw-tooth current waves; and

Fig. 3 is a curve showing the potential of grid 34 of tube 35 in Fig. 2, as a function of time.

Referring to Fig. 1 of the drawing, there is illustrated an impulse generator 1, which is not self-oscillatory. Tubes 2 and 3 are connected through condensers 4 and 5 and resistors 6, 7 and 8 in a circuit of the multivibrator type. Generator 1 is preferably synchronized by applying impulses of positive polarity to the control grid of tube 2. This circuit is externally excited inasmuch as, upon arrival of an impulse from an impulse generator (not shown) of any known type capable of producing a periodical train of rectangular impulses, it initiates an impulse which is terminated by an impulse derived from the remaining part of the circuit, as will be seen later. The impulses produced by the generator 1 are supplied through conductor 17 and condenser 18 to control grid 19a of discharge tube 19. This tube when conductive forms a discharge path for charging condenser 20. Condenser 20 is charged through resistor 21. As condenser 20 becomes positively charged, the control grid 26a of tube 26 becomes more positive and the plate current in tube 26 rises, causing an increasing voltage drop across resistor 15 in the plate circuit of tube 26. At the proper time during the charging period of condenser 20, when the voltage drop across resistor 15 has reached the desired value, an impulse is initiated by generator 1 which renders discharge tube 19 conductive, whereupon condenser 20 starts to discharge through resistor 22 and tube 19. During this discharge, the point 16 becomes more positive and finally reaches a value at which diode 23, biased by means of voltage source 27, becomes conductive. This causes an impulse to be applied to the control grid of tube 3, causing this tube to become conductive and thus terminating the impulse applied to tube 19, which thereupon becomes non-conductive. Condenser 20 then starts to charge again, and the cycle repeats itself. A saw-tooth voltage can be taken from the terminals 24 and 25. Thus it may be seen that if generator 1 is held at a constant frequency, for instance by means of injected synchronizing impulses supplied by any source (not shown) of square-topped impulses, the saw-tooth voltage amplitudes will remain constant because the duration of the condenser charging time is fixed by the interval between synchronizing impulses.

and the duration of the discharge time is fixed by a predetermined potential level reached by condenser 20 at the desired terminating point of the discharge period.

Referring to Fig. 2 of the drawing, a charging condenser 53 is charged through resistors 46, 47, 54 and 55 and periodically discharged through resistor 41 and electron discharge tube 35, when the latter is rendered conductive. The potential acquired by condenser 53 is applied to the control grid 42 of tube 43, causing a saw-tooth current wave to flow through scanning coil 44 connected between plate 43a and screen grid 51 of tube 43. The combination, consisting of resistors 45, 46, 47 and choke coil 48, serves to cause an adjustable amount of the direct plate current of tube 43 to flow through scanning coil 44, thus establishing a steady magnetic field used for centering the cathode ray beam in a television tube (not shown). The magnitude of this steady field can be varied by adjusting resistor 46. Condensers 49 and 50 are by-pass condensers employed for filtering the centering current.

During the charging period of condenser 53, tube 35 is non-conductive. This tube is connected as an externally excited relaxation oscillator, which is not self-oscillatory. Such circuits are known in the art. Figure 3 shows the voltage on suppressor grid 34 of tube 35 as a function of time, the dotted line representing the value which the voltage on suppressor grid 34 must exceed before current may flow to the plate of tube 35. During the non-conductive state of tube 35, condenser 36, which was previously negatively charged as will be explained below, discharges through resistors 46, 47 and 58 and variable resistor 33 by means of which the discharge time can be varied. Suppressor grid 34 becomes more positive and would finally render the tube conductive. These synchronizing impulses may be generated by any suitable generator (not shown) of periodical square-topped waves, as is well known in the art. Before this happens, however, a synchronizing impulse of positive polarity is applied at terminal 30, and reaches suppressor grid 34 through condenser 32, rendering tube 35 conductive. Thereupon, condenser 53 starts to discharge through resistor 41 and tube 35. The plate current in tube 43 decreases, and the cathode of tube 43 becomes less positive, as the voltage drop across cathode resistor 56 decreases. This in turn applies an increasingly negative potential to the cathode of diode 59, which is directly connected to the cathode of tube 43, so that diode 59 becomes conductive when the plate current in tube 43 has decreased to a certain value. When tube 59 is rendered conductive, a negative impulse is applied to screen grid 37 of tube 35, blocking this tube immediately. A negative charge is thereby also conveyed to condenser 36 which is also connected to lead 60 between screen grid 37 and the anode of diode 59. Tube 35 is rendered non-conductive, condenser 53 begins to charge again, plate current through tube 43 starts to rise and condenser 36 begins to charge, and the cycle repeats itself.

The plate of tube 35 is coupled with control grid 38 through condenser 40, a grid resistor 39 being connected between control grid 38 and the cathode as shown. Resistors 58, 54 and 55 constitute a voltage divider. By-pass condenser 57 is provided for the current impulse through diode 59.

It may be seen that the potential of a condenser allowed to charge and periodically discharge is used to control the current in an electron discharge tube and its load circuit, in such a manner that the condenser is discharged to a certain predetermined value.

It will be understood that other methods of operating the discharge path of the charging condenser can be used within the scope of this invention.

What I claim is:

1. A saw-tooth wave generator comprising in combination a first electron discharge tube having a cathode, a control grid and an anode, a condenser coupled to said cathode and said control grid for controlling the flow of current in said tube in accordance with voltages developed across said condenser, a resistance element coupled to said anode and said cathode for developing a voltage drop thereacross in accordance with the flow of current in said tube, means for charging said condenser, means for discharging said condenser including a second electron discharge tube, means for rendering said discharge means operative, and a biased rectifier responsive to a predetermined value of the voltage drop across said resistance element and effectively coupled to said discharging means for rendering said last-named means inoperative.

2. A saw-tooth wave generator comprising in combination a first electron discharge tube having a cathode, a control grid and an anode, a condenser coupled to said cathode and said control grid for controlling the flow of current in said tube in accordance with voltages developed across said condenser, a resistance element coupled to said anode and said cathode for developing a voltage drop thereacross in accordance with the flow of current in said tube, means for charging said condenser, means for discharging said condenser including a second electron discharge tube, a non-self-oscillating pulse generator adapted to initiate pulses, means for applying said pulses to said discharging means to render said last-named means operative, and a biased rectifier responsive to a predetermined value of the voltage drop across said resistance element and coupled to said generator for applying pulses thereto for terminating said pulses initiated by said generator and rendering said discharging means inoperative.

3. A saw-tooth wave generator comprising in combination a first electron discharge tube having a cathode, a control grid and an anode, a condenser coupled to said cathode and said control grid for controlling the flow of current in said tube in accordance with voltages developed across said condenser, a resistance element coupled to said anode and said cathode for developing a voltage drop thereacross in accordance with the flow of current in said tube, means for charging said condenser, means for discharging said condenser including a second electron discharge tube, means for rendering said second discharge tube conducting, and a biased rectifier responsive to a predetermined value of the voltage drop across said resistance element and coupled to said discharge tube for rendering said last-named tube non-conducting.

ULRICH KNICK.
